UNITED STATES PATENT OFFICE.

VITALIS HIMMER, OF MOUNTAIN LAKES, NEW JERSEY.

DESIGN FOR A LOUD SPEAKER.

Application filed December 24, 1927. Serial No. 24,640. Term of patent 7 years.

To all whom it may concern:

Be it known that I, VITALIS HIMMER, a citizen of the United States, residing at Mountain Lakes, in the county of Morris and State of New Jersey, have invented a new, original, and ornamental Design for Loud Speakers, of which the following is a specification, reference being had to the accompanying drawing, forming part thereof.

In the drawing—

I claim:

The ornamental design for a loud speaker, as shown.

VITALIS HIMMER.
